UNITED STATES PATENT OFFICE.

HOWARD M. DUDLEY, OF PHILADELPHIA, PENNSYLVANIA.

DYEING-MACHINE.

1,258,546.

Specification of Letters Patent.

Patented Mar. 5, 1918.

Application filed January 31, 1917. Serial No. 145,786.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to a dyeing machine and refers particularly to a machine adapted for the dyeing of textile fibers compressed within a dyeing chamber, the dyeing being accomplished by the forced passage of the dye liquor through the fiber mass.

Among the objects of my invention is a dyeing machine particularly suitable for the dyeing of warps in the ball, whereby the condition of the fiber may be accurately and readily judged at any stage of the treatment without opening the dyeing chamber and whereby even results may be obtained without disturbing the fiber to be dyed.

Another object of my invention is a dyeing machine in which the dyed goods may be after-treated with water, steam, air or other materials or substances without handling the dyed goods.

Other objects of my invention will be evident upon a consideration of my specification and claims.

I have found that the even or uneven dyeing results obtained in a machine of this general character depend largely upon the particular shape of the openings through which the dye liquor enters the fiber mass, and that unevenness can be prevented by the use of openings of a particular shape, the conformation of which enables the liquor to spread itself through the fiber mass without the formation of channels of flow.

I have further found that this desirable result can be obtained if the fiber-mass is supported in the dyeing chamber upon several series of upwardly converging elements, as cones or pyramids, arranged along longitudinally disposed openings.

In the use of many dyestuffs it is necessary, after dyeing, to treat the dyed goods with water for washing purposes, or with solutions of chemicals such as metallic salts or oxidizing products, for the purpose of after-treatment, or with oxygen or air for oxidizing or drying purposes. In the fol-

lowing of these after-treatments it is essential that every portion of the dyed goods be thoroughly and uniformly treated and that the operation be performed as readily and quickly as possible. All of these results are obtainable by the use of the device of my invention, in which the goods are placed in the dyeing chamber and then rapidly, easily and completely dyed and after-treated without further handling of the goods and without the formation of channels by the liquids employed. The device therefore insures even and uniform results with a minimum of time, labor, and expense.

One form of my device is shown in the accompanying drawings in which similar parts are designated by similar numerals.

Figure 1 is a side view of one form of my invention, partly broken away to disclose a portion in cross-section.

Fig. 2 is a broken cross-section through the line 2—2 of Fig. 1.

Fig. 3 is a broken enlargement of a cross-section of the foraminous plate of Fig. 1.

Fig. 4 is an enlargement of two of the elongated cones of Fig. 1 showing the method of attachment to each other.

Fig. 5 is an end view of Fig. 4.

Fig. 6 is a top-plan view of Fig. 4.

Fig. 7 is a broken top-plan view of a modification of the foraminous plate.

Fig. 8 is a cross-section through the line 8—8 of Fig. 7.

Fig. 9 is an enlargement of two of the elongated pyramids used as a modification of the elongated cones in Fig. 1.

Fig. 10 is a side view of Fig. 9.

Fig. 11 is a top-plan view of Fig. 9.

Fig. 12 is a cross-section of a modified top member.

The outer portion of the dyeing machine, as illustrated, comprises the upwardly converging cover 12 removably attached to the annular member 13 by the screw bolts 14, 14, the member 13 being movably attached to the shell 15 by means of the screw bolts 16, 16, the shell 15 being attached to the shell 17 by the bolts 18, 18, the shell 17 being attached to the downwardly converging shell 19 by the bolts 20, 20, the shell 19 being attached to the centrifugal pump 21 by the bolts 22, 22. The pipe 23 connects the chamber of the pump 21 with the three-way pipe 24, the latter having the pipes 25, 26 and 27.

fitted respectively with the valves 28, 29 and 30. The pipe 25 is connected with an air compressor, not shown; the pipe 26 opens into the air and the pipe 27 may be connected with a drain or receptacle as desired. The pump 21 is connected with the pipe 31, which in turn is connected with the pipe 32, the latter being connected with the pipe 33 carrying the valve 34, the pipe 35 carrying 10 the valve 36 and the pipe 37 carrying the valve 38. The pipe 33 is connected with a dye-dissolving tank, not shown, the pipe 35 is connected with a liquor-reserve tank 39, and the pipe 37 is connected with a water 15 supply.

The object of the reserve tank 39 is to allow of the production and use of a larger quantity of dye liquor than is necessary to fill the dyeing device. By this means the 20 strength of the dye-liquor may be governed to meet the requirements of each individual dyeing operation, and the liquid maintained in a condition where the dye will not be precipitated upon the fiber. It also allows a 25 more uniform supply of liquor to the pump 21.

The annular member 13 is of angular shape, one arm of which 40 fits within the interior face of the shell 15 and is slidable 30 therein, its vertical movement being governed by means of the screw-bolts 16, 16 which thread in the projections 41, 41 of the shell 15.

The pipe 42 connects the upper portion of 35 the interior of the shell 15 with the liquor reserve tank 39 and carries the valve 43. The pipe 44, carrying the valve 45 may be connected with a drain, not shown.

A fixed fiber-supporting plate 46 is situated 40 between the shells 15 and 17 and comprises a series of parallel grate-bars 47, 47, the bars of which carry upwardly and downwardly inclined cones 48, 48, allowing the openings 49, 49 between the grate-bars.

45 The device is provided with a movable annular foraminous plate 50, the construction of which is similar to the foraminous plate 46.

In order to facilitate reference to the 50 various chambers, they will hereafter be referred to as the top chamber 51, the dyeing chamber 52, the liquor-supply chamber 53, and the lower chamber 54.

A sample dyeing machine 55 exactly similar 55 to the one above described except that it is in smaller proportion and carries the threaded closed top 56 instead of the top 12, is connected to the liquor-supply chamber 53 by the pipe 57 carrying the valve 58. The 60 upper portion of the sample machine 55 is connected with a pipe 59, capable of being revolved into the position shown by the dotted line 60.

A pipe 61 connects the thermometer 62 65 with the liquor-supply chamber 53, the pipe

61 being extended beyond the thermometer into the pipe 63, capable of being revolved into the position shown by the dotted line 64.

A perforated steam pipe 65 is within the liquor supply chamber 53.

The top chamber 51 contains a number of 70 series of upwardly converging cones 66, 66 supported by the diamond-shaped bars 67, 67. Series of similarly shaped downwardly converging cones 68, 68, supported by the 75 members 69, 69, are situated within the lower chamber 54.

The operation of the device is as follows:

The top 12, the annular member 13 and the foraminous plate 50 are removed, and 80 the goods to be dyed introduced into the dyeing chamber 52 upon the foraminous plate 46. The foraminous plate 50 is then placed upon the goods, and the annular member 13 introduced and moved downwardly by means of the screw bolts 16, 16 threaded in the projecting members 41, 41, the annular member 13 pressing upon the foraminous plate 50. This downward movement of the annular member 13 and the 85 foraminous plate 50 is continued until the proper pressure has been obtained upon the goods in the dyeing chamber 52. Goods are similarly placed in the sample device 55. Valves 45, 28, 29, 30, 38 and 34 are 90 closed and valves 58, 43, and 36 are opened, and the pipes 59 and 63 situated as shown by the dotted lines 60 and 64. The necessary dyestuff having been dissolved in the 95 dye-dissolving tank, not shown, connected with the pipe 33, the valve 34 is opened and the centrifugal pump 21 is started. The pump 21 forces the dye liquor upwardly 100 between the cones 68, 68 in the bottom chamber 54, the liquor supply chamber 53, the 105 foraminous plate 46, the dyeing chamber 52 and the goods contained therein. As the liquor rises it will pass through the overflow pipe 42 into the liquor-reserve tank 39, from which it will pass through the pipe 35 110 into the pump 21, thus allowing of a continuous circulation of the dye-liquor upwardly through the device. During this operation the dye-liquor is forced upwardly through the sample device 55 and the goods 115 contained therein. The temperature is varied by means of steam introduced through the steam-pipe 65 and the temperature determined by means of the thermometer 62. From time to time, the valve 58 is 120 closed, the top 56 of the sample device 55 removed and the goods contained therein examined to determine their condition, and the top 56 replaced and the valve 58 opened and the dyeing operation continued until a 125 test of the goods in the sample device shows them to be properly dyed.

The next step is the removal of the dye-liquor contained in the device. This is accomplished by closing valves 43, 34 and 36, 130

opening valve 30 and stopping the pump 21. This allows all of the dye-liquor in the device to drain through the pipe 27 into a suitable receptacle for future use if desired.

5 The next step is that of washing the excess of dye-liquor from the goods and this is accomplished by closing valve 30 and opening valves 38 and 45, and starting pump 21. This allows fresh water to enter 10 through the pipes 37, 32 and 31 into the pump 21 which forces it upwardly through the device and the goods contained therein and through the overflow pipe 44 into a drain.

15 The next step is that of oxidizing the dyeings, if oxidizable, by means of air or of drying the goods. This is accomplished by placing the pipes 59 and 63 in the position shown by the full lines, placing the top 12 upon the device, affixing it thereto by means of the screw-bolts 14, 14, and attaching the upper open end of the top 12 to a vacuum or suction pump, not shown. The valves 45 and 38 are closed, the valve 29 is opened, 25 and the pump 21 stopped. The vacuum or suction pump attached to the top 12 thus draws air through the pipe 26 upwardly through the device and the goods contained therein. If the amount of air thus obtained 30 is insufficient for the purposes desired, the valve 28 connecting the pipe 25 with an air compressor may be opened and the valve 29 closed and thus sufficient air may be obtained. It is evident that the air passing 35 through the pipes 25 and 26 may be heated before its introduction into the device, if desired.

The particular formation of the foraminous plate 46 causes the dye liquor to be 40 spread out and evenly distributed through the goods causing even dyeings, the plate 50, because of its similarity to the plate 46, causes a more regular pressure of the dye liquor within the dyeing chamber 52 and 45 the conical members 66, 66 and 68, 68 intensify this distribution and regularity of pressure.

It is to be further noted that the goods are dyed, washed and after-treated or dried 50 without handling, and that all of the operations are under exactly the same conditions, and that the condition of the goods being dyed or treated can be determined at any time during the operation without interrupting the operation by examining the goods in the sample device 55.

In the modification shown in Figs. 7, 8, 9, 10 and 11, the foraminous plates 46 and 50 of Fig. 1 comprise a series of parallel 60 grate bars 70, 70, the bars of which carry upwardly and downwardly inclined pyramids 71, 71, allowing the openings 72, 72 between the grate-bars, and the top chamber 51 and the bottom chamber 54 contain 65 respectively a number of series of upwardly

converging and downwardly converging pyramids 73, 73 supported by the diamond-shaped bars 74, 74. In this modification it is advisable to have the top 12, the member 13 and the shells 15, 17 and 19, and the 70 pump 21 of a rectangular shape, the sample device 55 being also rectangular.

In the modification shown in Fig. 12, the top 12 of Fig. 1 is replaced by the dome-shaped top 75, which is attachable to the 75 member 40 by means of the screw-bolts 76, 76.

I do not limit myself to the particular size, shape, number or arrangement of parts as illustrated and described, as any or all 80 of them may be varied without going beyond the scope of my invention as described and claimed.

What is claimed, is:

1. In a dyeing machine, in combination, a 85 receptacle, a foraminous plate comprising a series of upwardly and downwardly convergent elements arranged along longitudinally disposed openings within the receptacle, a second foraminous plate similar to 90 and above the first plate, means for maintaining the second plate at varying distances from the first plate, a fiber chamber between the plates and the walls of the receptacle and means for forcing a liquid through the 95 openings in the second plates.

2. In a dyeing machine, in combination, a receptacle, a foraminous plate comprising a series of upwardly and downwardly convergent elements arranged along longitudinally disposed openings within the receptacle, a second foraminous plate similar to 100 and above the first plate within the receptacle, means for maintaining the second plate at varying distances from the first 105 plate, a fiber chamber between the plates, a series of downwardly converging members below the first foraminous plate, a series of converging members above the second foraminous plate, means for forcing a liquid 110 between the series of converging members, a reserve tank, means for conducting the liquid from the top of the receptacle to the reserve tank and means for conducting the liquid from the reserve tank to the forcing 115 means.

3. In a dyeing machine, in combination, a receptacle, a foraminous plate comprising a series of upwardly converging elements arranged along longitudinally disposed openings within the receptacle, a second foraminous plate within the receptacle and above the first plate, means for maintaining the second plate at varying distances from the first plate, a fiber chamber between the plates, a liquid supply chamber below the first plate, a chamber below the supply chamber, a series of downwardly converging members within the last-mentioned chamber so arranged as to allow the passage 120 125 130

between them of a liquid from a pump chamber to the supply chamber, a pump chamber and means for forcing a liquid through the receptacle.

- 5 4. In a dyeing machine, in combination, a receptacle, a foraminous plate comprising a series of upwardly converging elements arranged along longitudinally disposed openings within the receptacle, a second foraminous plate within the receptacle and above the first plate, means for maintaining the second plate at varying distances from the first plate, a fiber chamber between the plates, a series of downwardly converging members below the first foraminous plate, means for forcing a liquid between the series of converging members and through the fiber chamber, and means for returning the liquid from the top of the receptacle to the 20 forcing means.

5 3. In a dyeing machine, in combination, a receptacle, a foraminous plate comprising a series of upwardly and downwardly converging elements arranged along longitudinally disposed openings within the receptacle, a second foraminous plate similar to and above the first plate within the receptacle, means for maintaining the second plate at varying distances from the first plate, a fiber chamber between the plates, a liquid supply chamber below the first plate, a chamber below the supply chamber, a series of downwardly converging members within the last-mentioned chamber so arranged as 30 to allow the passage between them of a liquid from a pump chamber to the supply chamber, a series of upwardly diverging members above the upper plate to allow of the passage of air, a pump chamber, a pump, 35 a reserve tank, means for conducting the liquid from above the fiber chamber to the reserve tank and means for conducting the liquid from the reserve tank to the pump.

45 6. In a dyeing machine, in combination, a receptacle, a foraminous plate comprising a series of upwardly converging elements arranged along longitudinally disposed openings within the receptacle, a fiber chamber adjacent to the foraminous plate and means 50 for forcing a liquid through the openings in the foraminous plate and the fiber chamber.

55 7. In a dyeing machine, in combination, a receptacle, a foraminous plate comprising a series of upwardly converging elements arranged along longitudinally disposed openings within the receptacle, a fiber chamber adjacent to the foraminous plate, a smaller testing device similar and proportionate to, and exterior to the larger device, connecting means between the devices below the foraminous plates to allow of the passage of a liquid, and means for passing a liquid through the two devices.

60 8. In a dyeing machine, in combination, a

receptacle, a foraminous plate comprising a series of upwardly and downwardly converging elements arranged along longitudinally disposed openings within the receptacle, a second foraminous plate similar to and above the first plate, means for maintaining the second plate at varying distances from the first plate, a fiber chamber between the plates, a liquid supply chamber below the first plate, a chamber below the supply chamber, a series of downwardly converging members within the last mentioned chamber so arranged as to allow the passage between them of a liquid from a pump chamber to the supply chamber, a smaller testing device similar and proportionate to, and exterior to the larger device, connecting means between the devices below the foraminous plates to allow of the passage of a liquid, means for passing a liquid through the two devices and a pump chamber.

90 9. In a dyeing machine, in combination, a receptacle, a foraminous plate comprising a series of upwardly and downwardly converging elements arranged along longitudinally disposed openings within the receptacle, a second foraminous plate above the first plate and within the receptacle, means for maintaining the second plate at varying distances from the first plate, a fiber chamber between the plates, a series of downwardly converging members below the first foraminous plate, a smaller testing device similar and proportionate to, and exterior to the larger device, connecting means between the devices below the foraminous plates to allow of the passage of liquid, a reserve tank, means for conducting the liquid from the top of the receptacle to the reserve tank, means for conducting the liquid from the reserve tank to the forcing means.

100 10. In a dyeing machine, in combination, a receptacle, a foraminous plate comprising a series of upwardly converging elements arranged along longitudinally disposed openings within the receptacle, a second foraminous plate similar to the first mentioned plate within the receptacle and above the first plate, means for maintaining the second plate at varying distances from the first plate, a fiber chamber between the plates, a liquid supply chamber below the first plate, a chamber below the supply chamber, a series of downwardly converging members within the last-mentioned chamber so arranged as to allow the passage between them of a liquid from a pump chamber to the supply chamber, a pump chamber, a top chamber above the fiber chamber, a series of upwardly converging members within the top chamber so arranged as to allow the passage of a liquid, means for forcing a liquid through the device, and means for conducting air through the device.

11. In a dyeing machine, in combination,

a receptacle, a foraminous plate comprising a series of upwardly and downwardly converging elements arranged along longitudinally disposed openings within the receptacle, a fiber chamber adjacent to the foraminous plate, means for forcing a liquid through the openings in the foraminous plate and the fiber chamber, and means for conducting air through the openings in the 10 foraminous plate and the fiber chamber.

12. In a dyeing machine, in combination, a receptacle, a foraminous plate comprising a series of upwardly and downwardly converging elements arranged along longitudinally disposed openings within the receptacle, a fiber chamber adjacent to the foraminous plate, a smaller testing device similar and proportionate to, and exterior to the larger device, connecting means between the 20 devices below the plates for the passage of a liquid, means for passing a liquid through the two devices and means for passing air through the two devices.

13. In a dyeing machine, in combination, 25 a receptacle, a foraminous plate comprising a series of upwardly and downwardly converging elements arranged along longitudi-

nally disposed openings within the receptacle, a second foraminous plate within the receptacle similar to and above the first plate, 30 means for maintaining the second plate at varying distances from the first plate, a fiber chamber between the plates, a liquid supply chamber below the first plate, a chamber below the supply chamber, a series 35 of downwardly converging members within the last-mentioned chamber so arranged as to allow the passage between them of a liquid from a pump chamber to the supply chamber, a top chamber above the fiber- 40 chamber, a series of upwardly converging members within the top chamber so arranged as to allow the passage of a liquid, a smaller testing device similar and proportionate to, and exterior to the larger device, connecting means between the devices 45 below the plates for the passage of a liquid, means for passing a liquid through the two devices and means for passing air through the two devices. 50

Signed at New York city, in the county of New York and State of New York, this 29th day of January, 1917.

HOWARD M. DUDLEY.
